UNITED STATES PATENT OFFICE.

FRANK DE LUCA, OF NEW YORK, N. Y.

REMOVABLE SHOE TIP.

Application filed March 26, 1924. Serial No. 701,919.

To all whom it may concern:

Be it known that I, FRANK DE LUCA, a citizen of United States, residing at New York, in the county of New York and State of New York, have invented certain new and useful Improvements in Removable Shoe Tips, of which the following is a specification.

- This invention relates to improvements 10 in shoe construction and has as its principal object to provide a cap whereby the front or toe part of a shoe is protected and re-enforced, and the life of the shoe thereby materially lengthened.
- 15 Another purpose is to produce such a device in the form of an attachment which may be applied to shoes already made or which may be attached at the time of their manufacture.
- 20 A still further aim is in the provision of means whereby the shoe may be subjected to the usual hard abuse commonly given by children and still retain its shape and endurance.
- 25 These and other analogous objects are attained by the novel construction and combination of parts hereinafter described and shown in the accompanying drawing, forming a material part of this disclosure, and 30 in which:—

Figure 1 is a side elevational view of a conventional type of shoe showing the invention as applied.

Figure 2 is a perspective view of the device ready to be attached to the shoe.

Figure 3 is a similar view of a modified form of the cap.

Figure 4 is a longitudinal sectional view, taken on line 4—4 of Figure 3.

40 Figure 5 is a transverse sectional view of the attachment.

Figure 6 is a fragmentary sectional view, showing the cap securing means.

Referring to the drawing in detail, the 45 numeral 10 designates the main portion or upper of the shoe having raised vamps 11 and attached to a sole 12 at the rear of which is a heel 13, these parts being in all respects of the usual type of construction.

A cap generally designated by the numeral 14 is fitted to surround the upper front part of the shoe, extending over the sides thereof, and is formed with a bevelled, inwardly extending lower edge 15, folded and crimped closely below the sole 12, this 55 cap being made of firm leather adapted to withstand the hard usage accorded it.

Below the inturned edge 15 is secured a 60 relatively thick, firm partial lift 16 having a bevelled rear edge 17 extending substantially co-incident with the rear edge of the cap 14 and its front and side edges allowed to project, forming a guard to make contact with obstacles as stones and the like, preventing damage to the toe of the shoe. 65

In the modification shown in Figures 3 and 4, a thin sheet of metal 18 is bent to 70 conform to the outer surface of the cap 14 and its lower edge held between the in-turned edge of the cap and the partial lift 16, as is clearly shown.

As shown in Figures 5 and 6 the shoe is 75 constructed with a double sole, that is to say an inner and outer sole, respectively 20 and 21, these elements having inserted in them, at spaced intervals along their edges cup-shaped semi-circular sockets 22 having stems 23 projecting between the soles, these sockets being receptive of the heads 24 of rivets 25 having their stems fixed in the cap 80 and upset so that the outer heads 26 impinge upon the surface of the caps 14, holding the cap structure firmly united to the toe of the shoe. In operation, the rivets are positioned in the cap, both ends formed into 85 round heads, one of which appears on the surface of the cap and the other, inner head sprung into engagement with the socket, which has been inserted in the sole of the shoe prior to placing the cap thereover. 90

The cap, carrying the rivets is then forcibly pressed over the toe of the shoe, the cap springing sufficiently to allow such disposition and eventually the inner heads engage the fixed sockets, holding the caps in operative position. 95

From the foregoing it will be seen that a substantial and practical form of shoe

cap has been disclosed, together with means for adequately securing the same in operative position.

Having thus described my invention, what I claim as new and desire to secure by Letters Patent, is:—

A shoe cap comprising a partial lift having a bevelled rear edge, a cap enveloping the toe of the shoe and having an inturned

edge fixed to said lift, metallic sockets fixed in spaced relation in the edge of the sole of the shoe, and rivets having heads set in said sockets and extending outwardly through said cap. 10

In witness whereof I have affixed my signature.

FRANK DE LUCA.
